UNITED STATES PATENT OFFICE.

ALFRED M. DEMUTH, OF CHICAGO, ILLINOIS.

INDIVIDUAL WORK-HOLDER FOR SLICING-MACHINES.

1,372,487.

Specification of Letters Patent. Patented Mar. 22, 1921.

Application filed July 26, 1920. Serial No. 399,124.

To all whom it may concern:

Be it known that I, ALFRED M. DEMUTH, a citizen of the United States, residing at Chicago, in the county of Cook and State 5 of Illinois, have invented certain new and useful Improvements in Individual Work-Holders for Slicing-Machines, of which the following is a specification.

This invention is particularly adapted 10 though not necessarily limited in its use with slicing machines embodying a carriage and a cutter relatively reciprocable one with relation to the other, the article being intermittently advanced to be projected to 15 the cutter during such relative movement, whereby slices of predetermined thickness may be severed therefrom.

It is customary to interchange the articles 20 upon slicing machines as occasion or necessity may require, and when one article is removed and then replaced it is impossible to replace the article so that the face from which the slices are to be cut will be square with or disposed in a plane parallel with 25 the cutting plane, with the result that the first few slices that are cut from the replaced article will be imperfect and broken slices and not of a uniform thickness, resulting in dissatisfaction to the customer or 30 loss to the merchant.

It is one of the objects of the present invention to provide an individual work holder for each of the articles to be cut and to which holder the article is fastened, so 35 that the article may be removed with the holder and again replaced in the machine with the holder. The article being secured to the holder will insure the proper positioning of the article with respect to the cutter 40 to insure a complete and perfect initial slice of a uniform thickness. At the same time, the use of such a holder will obviate the necessity of the merchant's hands constantly coming into contact with the article, thereby 45 insuring sanitary conditions.

A further object is to provide an improved individual holder of this character having improved means for securing the article thereto while the holder is either in or out 50 of the machine.

To the attainment of these ends and the accomplishment of other new and useful objects as will appear the invention consists in the features of novelty in substan-

tially the construction, combination and arrangement of the several parts hereinafter more fully described and claimed and shown in the accompanying drawings illustrating this invention and in which—

Figure 1 is a front elevation of a slicing 60 machine table having this improved attachment applied thereto.

Fig. 2 is a top plan view of the parts shown in Fig. 1 and also showing a portion 65 of the cutter.

Fig. 3 is a vertical sectional view taken on line 3—3 Fig. 1.

Fig. 4 is a detail perspective view of the work holder removed and with the clamping bar omitted therefrom.

Fig. 5 is a perspective view of a slightly modified form of the work holder removed from the machine and showing the clamping bar in position.

Fig. 6 is a detail perspective view of one 75 end of the clamping bar.

Referring more particularly to the drawing the numeral 10 designates the table of a slicing machine which in the present form of the invention is adapted to reciprocate 80 with respect to the cutter 11 as usual in machines of this character.

The table 10 is mounted thereon and the work support 12 which is adapted to be intermittently advanced with respect to the 85 table 10 at predetermined points in the relative movement of the table and the cutter, as is also common in machines of this character.

This work support 12 is provided with the 90 usual toothed uprights 13 and 14, and movable thereupon is the usual clamping bar 15.

The individual or supplemental work holder embodies a support 16 which is preferably provided with upstanding edges or 95 flanges 17 and is also preferably provided with a series of apertures 18 opening through the front edge thereof and a plurality of slots 19 opening through the body of the holder.

The upper edges of the flanges 17 preferably taper toward the rear of the supplemental support 16 for the purpose of lightness and this supplemental support 16 is preferably of a size substantially equal to 105 the work support 12.

Projecting upwardly from one of the sides 16 of the supplemental support is an

upright 20 provided with a series of angular shaped apertures or slots 21 and this upright 20 may be formed separately from the supplemental support and secured thereto 5 by means of suitable fastening devices 22, or, if desired may be formed integral therewith.

Arranged on the opposite side of the holder is another upright 23 having a series 10 of slots 24 opening through one edge thereof. This upright 23 is pivotally connected with the support and has a handle 26 by means of which the upright may be moved about its pivot, the direction of pivotal 15 movement being transverse to the cutting plane. A pin 27 is preferably connected to the upright 23 and is adapted to operate in a slot 28 so as to limit the pivotal movement of the upright 23.

20 These uprights 20 and 23 are arranged adjacent but are preferably spaced back of the front edge of the supplemental support 16 and which edge contains the openings 18.

25 A suitable clamping bar 29 co-operates with the uprights 20 and 23. This clamping bar may be of any desired size and configuration and is provided with teeth 30, and one end 31 of the bar is preferably reduced or shaped to form an angular extremity adapted to be inserted into and to conform with the apertures 21 in the upright 20. The other end of the bar 29 is provided with a suitable handle 32 and is also provided with a reduced portion 33 30 adapted to enter the slots 24 for holding the clamping bar in position.

35 In use, the article is placed upon the supplemental support 16, the clamping bar 29 being first removed. When the article is 40 placed upon this support it is arranged so that a portion thereof will project beyond the front edge of the supplemental support. The clamping bar 29 is then placed in position by inserting the end 31 thereof in the desired opening 21 of the upright 20. The handle 32 of the bar 29 is then depressed so as to force the teeth 30 of the bar into the article. The upright 23 before the bar is 45 placed in position is moved about its pivot 25 into the position shown in dotted lines in Fig. 3. When the bar is placed in position as just above described, the handle 32 is held depressed and the upright 23 is moved by the handle 26 about its pivot 25 so that the 50 reduced portion 33 of the bar will enter one of the slots 24. This, as will be seen, will securely fasten the article to the supplemental support.

55 The supplemental support with the article thereon is then placed in position upon the work support 12 of the machine so that the openings 18 in the front edge of the supplemental support will be in positions to receive the pins 34 on the work support 12.

The clamping bar 15 on the work support 65 12 is then moved downwardly upon the uprights 13-14 until it engages and clamps the article upon the work support.

When the parts are in this position the slicing machine is operated and the supplemental support will be intermittently advanced with the work support.

When it is desired to interchange the articles the clamp 15 is raised and the supplemental support with the article fastened 75 thereupon may be removed from the work support while the rest of the machine is intact by simply raising the supplemental support from the machine by the handles 35. When the supplemental support is in position 80 the slots 19 will receive the pins 36 which are mounted upon the work support 12.

With this improved construction it will be seen that when an article is replaced in 85 the machine together with the supplemental support the front edge, or the face from which the slices are to be cut will be arranged in a plane parallel with the cutting plane so that the first slice will be a complete unbroken slice of a uniform thickness.

90 The articles being secured to the holder, can be readily placed therewith into the ice box or upon the counter thereby obviating 95 the necessity of the merchant handling the articles when they are interchanged in the machine.

95 As shown in Fig. 5, the supplemental support 37 may be provided with a series of ribs 100 or corrugations 38 extending lengthwise of the support and in a direction transverse to the line of cut. The crown of each of the corrugations is preferably flattened so as to 105 form sharp edges 39 so that when the article is clamped upon the supplemental support the edges of the corrugations will embed 110 themselves in the article and will hold the article against a lateral shifting movement when the knife or cutter contacts with the article.

115 While the preferred form of the invention has herein been shown and described, it is to be understood that various changes may be made in the details of construction and in the combination and arrangement of the several parts within the scope of the claims without departing from the spirit of this invention.

120 What is claimed as new is:—

1. A device of the character described embodying a main support, an upright connected therewith, an individual work holder, a clamping element movable upon the upright and adapted to clamp the article carried by the said holder, said holder being attachable and removable at will while the clamping member is carried by the upright,

ment is connected with the said upright, the article engaging surface of the said supplemental support being provided with corrugations extending lengthwise of the said surface and in a direction transverse to the line of cut of the article.

11. A device of the character described, embodying a main support, an upright connected therewith, a supplemental support, 10 a clamping element carried with the supplemental support, a clamping element movable upon the upright and adapted to engage and clamp the article carried by the supplemental support, said supplemental support

being attachable and removable at will while 15 the second recited clamping element is connected with the said upright, the article engaging surface of the said supplemental support being provided with corrugations, the said corrugations extending lengthwise of 20 the said surface and in a direction transverse to the line of cut of the article, the crowns of the corrugations being shaped to form spaced narrow article engaging edges.

In testimony whereof I have signed my 25 name to this specification, on this 2nd day of July, A. D. 1920.

ALFRED M. DEMUTH.
